(No Model.)

S. C. NORTON.

CAR DOOR LOCK.

No. 300,325.

Patented June 10, 1884.

UNITED STATES PATENT OFFICE.

SAMUEL CLARK NORTON, OF HINCKLEY, MINNESOTA, ASSIGNOR TO MAGGIE L. NORTON, OF SAME PLACE.

CAR-DOOR LOCK.

SPECIFICATION forming part of Letters Patent No. 300,325, dated June 10, 1884.

Application filed September 24, 1883. (No model.)

To all whom it may concern:

Be it known that I, SAMUEL CLARK NORTON, a citizen of the United States, and a resident of Hinckley, in the county of Pine, in the State 5 of Minnesota, have invented certain new and useful Improvements in Car Lock and Seal Combined, of which the following specification is a full, clear, and exact description, reference being also had to the accompanying drawings, 10 in which—

Figure 1 is a side view. Fig. 2 is a vertical sectional view of a portion of a freight-car provided with my lock and seal, and Fig. 3 is a horizontal sectional view of a portion of a 15 freight-car with my improved lock attached thereto. Fig. 4 is an enlarged front view of the same. Fig. 5 is an enlarged longitudinal sectional view of the lock on the line $x-x$ of Fig. 1. Fig. 6 is an enlarged sectional view 20 of the lock on the line $y-y$ of Fig. 5, and Fig. 7 is an enlarged cross-sectional view on the line $z-z$ of Fig. 6. Fig. 8 is an enlarged detached perspective view of the door-holding bolt. Fig. 9 is a similar view of the graduated 25 wheel and the ratchet. Figs. 10 and 11 are perspective views showing the form of the bolt and hasp when soft-metal seals or similar fastenings are to be used. Fig. 12 is a perspective view, detached, of the locking-lever. 30 Fig. 13 is a perspective view of the graduated drum.

This invention relates to the fastenings of the doors of freight-cars; and it consists in a bolt for holding the door closed, which is actuated by a spring or other means, and adapted, when it springs out to lock the door, to turn a graduated wheel or drum and expose to view a certain number or mark to denote the station where the door was last closed, as 40 hereinafter shown.

The invention further consists in providing means for using soft-metal seals or other similar means for securing the door, as hereinafter shown.

45 In the drawings, A represents the frame or body of the car; B, the door, arranged to slide upon a "way," a, in the ordinary manner.

C is a metal frame or casing embedded in the side of the car, just in the rear of the door B, 50 when the latter is closed, and provided with a spring-bolt, D, adapted, when pressed out-

ward by the spring b, to hold the door closed, as shown in Figs. 1, 2, and 3.

E is a small lever, pivoted at c in the casing C, and having a right-angled end, d, held up 55 into a socket, e, (see Fig. 8,) in the bolt by a spring, g, so that the lever will lock the bolt D outward, as shown in Figs. 5 and 7.

F is a key adapted to be inserted through a key-hole, h, in the face of the casing C, to throw 60 the lever E downward and release the bolt D, so that it may be pushed in to enable the door B to be opened.

Mounted upon the pivot of the bolt D, or at any other suitable point in the casing C, is 65 a graduated drum or wheel, G, and ratchet-wheel H, the graduations of the drum and the teeth of the ratchet corresponding in number.

i is a small spring-pawl pivoted to the bolt D, and engaging with the teeth of the ratchet 70 H, so that the movement of the bolt will be communicated to the ratchet and drum.

The graduations on the periphery of the drum will be numbered, lettered, or otherwise marked to enable them to be easily distinguished, and may be of any required number. In the drawings I have shown them numbered from 1 to 18; but any greater or lesser number may be used, if desired. The casing C has a hole, m, cut through it opposite the 75 center of the drum G, and the throw of the bolt D and the length of the teeth on the ratchet H will so correspond that each stroke of the bolt will revolve the drum the distance of one of its graduations; hence each movement of the bolt will expose a different number to view through the hole m. The lower face of the drum G will be provided with a series of holes, r, in a circle concentric with the outer rim of the drum, and corresponding 80 in number with the graduations and ratchet-teeth, into one of which a small pin, w, on the lever E fits when in the position shown in Fig. 6, to hold the drum and prevent its being turned from the outside through the hole m. 85 When the ordinary lead or other soft-metal seals or similar fastenings are to be used either in addition to or in place of the ratchet and drum G H, I form the outer end of the bolt D with a slot, r, into which a bolt or hasp, K, 90 attached to the door B, fits when the door is closed, and insert the lead seal or other fast-

ening through holes *t* in the bolt and hasp. When a car is loaded and the door closed, the bolt *D* will spring out behind it and hold it closed, and at the same time the lever *E* will 5 catch the bolt and prevent its being pushed in again unless the lever be released by the key *F*. The springing out of the bolt *D* sets and fixes the position of the drum *G*, so that whatever letter, figure, or other mark is exposed to view through the hole *m* will remain until the door is again opened, when the next mark will be exposed. When the door is first 10 closed, the person having charge of the billing of the cars records on the bill with the number or other distinctive mark of the car the number exposed through the hole *m*. Then, if the car contains through-freight, the agent at the 15 end of the line can know, by comparing the bill with the lock-number, whether the car has been opened during its transit. If the car contains way-freight, then the agent opening the car will record upon the bills the numbers exposed both before and after opening, so that the bills will show at what stations the 20 car was opened. By this simple means a perfect check is secured upon the conductors and freight agents, and enables the railroad officials to locate all the points at which the cars 25 are opened.

Having described my invention and set forth 30 its merits, what I claim is—

1. The combination of a sliding car-door, a bolt, *D*, located in the body of the car and adapted to be thrown out and locked against the end of the door, a graduated drum, *G*, and 35 mechanism connecting the bolt and drum, whereby the movement of the bolt for locking against the door moves the drum, substantially as and for the purpose herein specified.

2. The combination, with a sliding car-door, 40 *B*, having hasp *K*, of the bolt *D*, having slot *r*, the said hasp and bolt having corresponding seal-openings, *t t*, and means for locking said bolt outward, substantially as described.

3. The combination of a car-door, *B*, a lock- 45 bolt, *D*, located in the car-body and adapted to be thrown out and locked against the end of the door, bolt-locking lever *E*, graduated drum *G*, provided with ratchet-teeth *H*, pawl *i*, and key *F*, substantially as and for 50 the purpose herein specified.

In testimony whereof I have hereunto set my hand in presence of two subscribing witnesses.

SAMUEL CLARK NORTON.

Witnesses:
